UNITED STATES PATENT OFFICE.

WILLIAM KENDALL, OF NORFOLK ISLAND, SOUTH PACIFIC OCEAN.

DESIGN FOR A CLAW-HAMMER.

SPECIFICATION forming part of Design No. 20,852, dated June 23, 1891.

Application filed May 5, 1891. Serial No. 391,691. Term of patent 14 years.

To all whom it may concern:

Be it known that I, WILLIAM KENDALL, of Norfolk Island, South Pacific Ocean, have invented and produced a new and original Design for Claw-Hammers, of which the following is a specification, reference being had to the accompanying drawing, which is a side view of a hammer, showing my design.

The leading feature of my design consists in a claw-hammer having an outline formed of two intersecting curves.

The upper outline *a* has an offset *b* and joins the curved outline *c*, extending above the straight line *a* and joining the curved line *d*. The end of the curved line *d*, which joins

the curved line *c*, forms an obtuse angle therewith. The other end of the curved line *d* joins the curved line *e*, forming an acute angle. The other end of the curved line *e* joins the first of a series of straight and curved lines extending to the upper outline and forming an angular outline, as shown.

I claim—

The design for a claw-hammer herein shown and described.

WILLIAM KENDALL.
